(57) **CLAIM**

The ornamental design for a strap for holding a pair of skis together, as shown and described.

DESCRIPTION

FIG. 1 is a perspective view of a strap for holding a pair of skis together showing my new design;

FIG. 2 is a top plan view thereof;

FIG. 3 is a bottom plan view thereof;

FIG. 4 is a right edge view thereof;

FIG. 5 is a left edge view thereof;

FIG. 6 is a left end view thereof;

FIG. 7 is a right end view thereof;

FIG. 8 is a perspective view showing the strap in folded operative position;

FIG. 9 is a perspective view showing the strap partially wound around a pair of skis; and,

FIG. 10 is a perspective view showing the strap completely wound around a pair of skis.

The parts shown in broken lines in FIGS. 9 and 10 are for information only, and form no part of the instant design.
